UNITED STATES PATENT OFFICE.

EDWARD LINDMUELLER, OF CLEVELAND, OHIO.

WASHING MACHINE.

Application filed October 27, 1920. Serial No. 419,849.

To all whom it may concern:

Be it known that I, EDWARD LINDMUELLER, a citizen of the United States, residing at Cleveland, in the county of Cuyahoga and State of Ohio, have invented certain new and useful Improvements in Washing Machines; and I do declare that the following is a full, clear, and exact description of the invention, which will enable others skilled in the art to which it appertains to make and use the same.

My invention relates to a washing and drying machine, especially designed for household use, in which the clothes or articles to be washed are washed in one device, and dried in another device; and the object of my invention, is to provide a machine which is simple in construction, efficient and economical in use, and which by reason of its design and construction, and manner of operation has exceptional possibilities as to speed and economy of movements, on the part of the operator, in doing the washing and drying.

I am aware that prior to my invention, washing machines have been made with revolving cylinders, also that the centrifugal method has been used for drying purposes. By means of my invention, the articles to be washed are placed in the washing cylinder, the cover attached and the power applied. After washing, the cleaned articles are transferred to the centrifugal drier, and revolved at a speed of 400 to 600 revolutions per minute. This action drives the water solution from the articles, and leaves them just damp. While the drier is operating, other articles are being washed in the cylinder. Usually the soapy water is driven from the articles; then they are placed in a rinsing tub, and dried again; then in a bluing solution, and dried again. The drying operation takes about 3 minutes, and the washing operation takes about 15 minutes. Thus by means of my invention there is no delay or waiting, and the operator can do up a washing, in far less time than by any means heretofore used, also with less effort. The articles are not pulled out of shape, or the buttons torn off, as occurs in the use of a roller wringer. Also my invention produces a machine, that is quiet in operation, and free from those nerve racking noises

and vibrations, commonly found in other washing and drying machines.

I attain these objects by the mechanism illustrated in the accompanying drawings, in which—

Fig. 1 is a longitudinal vertical section taken along line 1—1 of Fig. 2 looking in the direction indicated by the arrows. Fig. 2 is a horizontal section taken along the irregular line 2—2 of Fig. 1 looking in the direction indicated by the arrows. Fig. 3 is an enlarged, part sectional view, of the reversing clutch and cam, which is shown in section, in Fig. 1. Fig. 4 is an enlarged sectional view of the intermittent gears, taken along the line 4—4 of Fig. 2 looking in the direction indicated by the arrows. Fig. 5 is a supplementary view, of the intermittent gears, shown in Fig. 4 but showing 4 teeth in the driver gear.

Referring now to the figures of the drawings, in which similar numerals, refer to similar parts, throughout the several views.

1, represents a suitable frame, shown as a channel, secured to legs 2, which rest on the floor. 3 is a transverse brace for the frame 1. 4 are transverse braces and supports for the clutch box. 5 is a transverse brace and support for the centrifugal pedestal. The washing cylinder 6 in which the articles to be washed are placed has a suitable number of holes 7, for the passage of the water, and an opening 8 and a removable cover 9. Secured to 6 is a support 10 having a trunnion 11, which revolves in the slotted bearing 12, in support 13. Secured to 6 is a support 14, having a square hole 15 engaging the squared end 16, of the drive-shaft 17. The container 18 having an opening 19, and a removable cover 20, holds the washing solution, and is supported by members 21, to frame 1, and drained by means of a suitable drain cock 22.

The cylinder 6, is revolved 6 revolutions in one direction and reversed for 6 revolutions continuously, until the washing is done. To prevent the articles being washed, balling up, or tying themselves in knots, it is essential that the cylinder 6, makes exactly the same amount of revolution in each direction. I accomplish this by means of the clutch and drive mechanism here shown.

The cylinder 6 can be lifted out of the

supporting means 13 and 16 very easily, by sliding toward the left and lifting. The drive shaft 17, has secured to it the bevel gear 23, meshing into gear 24, secured to the vertical shaft 25. The bevel clutch-gears 26 and 27 revolve on shaft 25 in opposite directions, being in mesh with the drive gear 28. The intermittent timing gear 29, has hub extensions secured to 28, and to worm-gear 31, which allows 28, 29 and 31 to revolve as one unit, on the stud 32, which is secured to the clutch-box 33. The worm-gear 31 is driven by worm 34, secured to shaft 35, which has secured to its outer end, gear 36, meshing into the motor gear 37 of the motor 38. The intermittent gear 30, is revolved one-twelfth of a revolution for each revolution of the one tooth gear 29. Fig. 4 shows the one tooth 39, of gear 29, in mesh with the recess 40, of gear 30, and Fig. 5 shows the periphery 42, of gear 29, revolving in the concave surface 41, of the periphery of gear 30, thereby preventing gear 30, from revolving until the tooth 39 comes around again, and engages the recess 40, thereby revolving gear 30 another one-twelfth of a revolution. Gear 30 is secured to shaft 43, and the cam 44 is secured to shaft 43. Referring to Fig. 3 the cam 44, has an inclined surface 45, and a radial surface 46, which control the movements of the plunger 47, which is slidably mounted in the oscillating clutch-lever 48. The springs 49, provide a pressure for the plungers 47, against the cam 44, and also serve as a cushioning means. When cam 44, revolves in the direction indicated by the arrow, the surface 45, compresses the plunger 47, thereby exerting a pressure in one direction, on the clutch-lever 48, and as the radial surface 46, passes the other plunger 47, this pressure oscillates the clutch-lever 48, in one direction and on the next half revolution of cam 44, in the other direction. The surfaces 45 and 46 are approximately diametrically opposite, and the plungers 47, have suitably shaped noses or ends, which allow their engagement with the periphery surface of cam 44. Fig. 1 shows the cam 44 in a position compressing both plungers 47, and the clutch-lever 48 in a neutral position, and Fig. 3 shows the action completed, with 48 at rest in one extreme position, being held by the plunger under compression, the other plunger being without compression, having followed the surface of cam 44. The clutch-lever 48, is suitably pivoted on pin 50, secured to clutch-box 33, a portion of it surrounding the cam 44, and at its other end having a fork, with pins 51, which engage the annular recess 53, in the revolving clutch-sleeve 52. The key 59, is secured to shaft 25, and the clutch-sleeve 52, engages this key, so as to revolve with shaft 25, but slidably in a vertical direction thereon, under the

control of the clutch-lever 48. At each end of the sleeve 52, suitable teeth 54, engage alternately the teeth 55 of the bevel gears 26 and 27. When the motor 38 is running, the bevel gears 26 and 27 run continuously, but in opposite directions, as indicated by the arrows, and thus when cam 44 oscillates the clutch lever 48, in one direction, then gear 26 is the driver of shaft 25, and in the other direction, then gear 27 drives clutch-sleeve 52, the shaft 25 and hence the cylinder 6. Suitable bearings are provided in the gear-box 33 for the shafts 17, 25, 35 and 43, and the plugs 56 prevent the oil or grease, which this box contains, from leaking out. Suitable packing is provided at 58, to prevent water from the container 18, reaching the bearing for shaft 17. A cover 57 is provided for 33, which is secured in place after the clutch mechanism is assembled.

In Fig. 5 I show 4 teeth in the intermittent driving gear 29, and 12 recesses in the gear 30. This gives 4 impulses to gear 30, for each revolution of gear 29, and hence only one and a half revolutions of washing cylinder 6, before reversing. By varying the number of teeth in 29, and the recesses in 30, a variety of revolutions can be given to cylinder 6, before reversing.

The articles to be dried are placed in the receptacle 60, which is provided with holes 61, and secured to shaft 62, by means of key 63, and nut 64. The pedestal-like support 65, has suitable bearings 66 and 67, for shaft 62, and lock-nuts or fillers 68 and 69, to secure these bearings. Suitable packing 70 and 71, is provided to prevent the escape of oil or grease, which is provided for lubricating the bearings 66 and 67. The bearing 66, is of the radial type, and bearing 67 is a combined radial and thrust type, taking the upward and downward thrust of shaft 62. Secured to shaft 62, is the bevel gear 72, meshing into gear 73, secured to the motor shaft 74, of the motor 75. Secured to the motor shaft 74, is a wheel or brake drum 76. The brake 77 actuated by the solenoid 78, is provided in order to rapidly reduce the speed of rotation of the shaft 74, and hence the receptacle 60, when the current to the motor 75 is cut off. A hand or spring actuated brake can be here provided, in place of the electrically operated brake. A transverse brace 79, secured to frame 1, supports the motor 75, and the solenoid 78. Secured to the upper end of the pedestal 65, is a flanged member 80, secured to the container 81, holding 81 concentric with the receptacle 60. A suitable drain 82, drains the solution from the container 81. Suitable electrical switches or push-buttons and wires are provided, but not shown on the drawings, to start and stop the motors 38 and 75. These are placed in convenient locations for the operator. The solenoid 78, is oper-

ated from the electrical circuit of motor 75, or as a separate unit.

In operating my invention, the clothes or articles to be washed are placed into the 5 washing cylinder 6, a suitable quantity of soap and water placed in the container 18, the covers 9 and 20 secured in place, the current turned into motor 38, and allowed to run about 15 minutes. The rotating and 10 reversal of cylinder 6, agitates the articles in the water, assisted by the cleats or strips in the cylinder, thoroughly washes them. The motor 38 is stopped, the covers 9 and 20 removed, and the articles transferred to 15 the receptacle 60. The current is turned into motor 75, which revolves the receptacle 60 at about 500 revolutions per minute. The liquid in the articles is forced by this 20 centrifugal action outwardly from the center of revolution, through the holes 61, and into the container 81, and is drained through the outlet 82, to the sewer or a 25 convenient receptacle. This centrifugal action is continued for a few minutes, the current cut out of motor 75, and the brake applied, which quickly stops the revolving 30 receptacle 60. The articles are then removed, and the operation repeated on other articles. Thus it can be seen that the washing and drying can be carried on simultaneously or separately and that the design 35 of my invention is such as will secure perfect results, quickly, with little effort, quiet mechanism, freedom from vibration, economy of power, safety, and the absence of the pulling of buttons or tearing of material.

I do not desire to be confined to the exact 40 details shown, but aim in my claims to cover all modifications which do not involve a departure from the spirit and scope of my invention.

Having thus described my invention, what 45 I claim and desire to secure by Letters Patent is:—

1. In a machine of the character described, a rotatable drum, gears for driving said drum in opposite directions, means including a Geneva movement and a clutch 50 shift lever for stopping and reversing the direction of movement of said gears, means including cushioned plungers on said shift lever for cushioning the stopping and reversing movements of said gears, and continuously driven means for actuating said gears.

2. In a gearing, the combination with power means and a driving shaft provided with a gear, and a second shaft provided with loosely mounted gears meshing with said gear, and a shiftable clutch sleeved on said second shaft between said last mentioned gears; of a third shaft provided with intermittent gears operatively connected to 55 said first mentioned shaft, a cam on said

shaft, and a clutch shift member provided with spring resisted plungers adapted to ride on said cam and to resiliently shift said lever and shiftable clutch.

3. In a gearing, the combination with power means and a driving shaft provided with a gear, and a second shaft provided with loosely mounted gears meshing with said gear, and a shiftable clutch sleeved on said second shaft between said last mentioned gears; of a third shaft provided with intermittent gears operatively connected to said first mentioned shaft, a cam on said third shaft, and a clutch shift member provided with spring resisted contact elements 70 adapted to ride on said cam to resiliently shift and cushion said lever and shiftable clutch.

4. In a reversible gearing, the combination with suitable continuously operating driving and driven gears, and a shiftable clutch for alternately engaging said gears; of intermittent gears in timed relation to said first mentioned gears, a shaft driven by said intermittent gears and provided with a cam, and a shiftable member operatively connected to said shiftable clutch and provided with spring resisted contact elements 85 in co-operative relation to said cam whereby to hold said shiftable member and clutch in neutral and shifted positions and to cushion the motion of the same.

5. In a reversible gearing, the combination with continuously operating driving and driven gears, and a shiftable clutch for 100 alternately engaging said driven gears; of intermittent gears in timed relation to said first mentioned gears, a shaft driven by said intermittent gears and provided with a cam, and a shiftable member operatively connected to said shiftable clutch and cam and provided with spring resisted cam contacts whereby to hold said shiftable member and clutch in neutral and shifted positions and to cushion the shifting impulses imparted 105 to the same.

6. A gearing for washing machines, comprising a power shaft provided with a gear, a second shaft provided with loose gears meshing therewith, a shiftable clutch on and adapted to drive said second shaft and adapted to be shifted into engagement with either of said loose gears, a third shaft, intermittent gears connecting said third and first mentioned shaft, a cam on said third shaft, and a lever between said cam and shiftable clutch whereby the latter is moved into and out of engagement with said loose gears to reverse the direction of rotation 115 of said second shaft.

7. A gearing for washing machines, comprising a power shaft provided with a bevel gear, a second shaft provided with a pair of gears meshing therewith, a shiftable clutch carried by said second shaft and 120

130

adapted to be alternately shifted into and out of engagement with said last mentioned gears, a third shaft, intermittent gears between said third and first mentioned shafts, 5 a cam on said third shaft, and a lever operatively connected between said cam and shiftable clutch whereby the latter is moved

into and out of engagement with said gears on said second shaft to reverse the direction of rotation of said second shaft.

10

In testimony whereof, I hereunto affix my signature.

EDWARD LINDMULLER.
